ABSTRACT

A shoe last having an embedded hollow member provided with a cutting edge projecting from the last bottom for cutting a tab in an insole forceably applied to the last bottom for holding the insole registered on the last bottom. A method for temporarily securing an insole on a last bottom in which the cut tab is received in the hollow member.

SHOE LAST WITH INSOLE ATTACHMENT MEANS
BACKGROUND AND OBJECTS OF THE
INVENTION

As a preliminary step in a sequence of operations involved in the lasting of shoes it is usually necessary to assemble an insole on the bottom of a last with considerable accuracy. It is common for the insole to be temporarily secured to the last so as not to be displaced during subsequent operations in the lasting of the shoe, but so as to permit the last to be slipped from the shoe at the required stage of the manufacture. It has already become well known for an insole to be positioned on a last by means of co-operation between apertures in the insole and projections, known as pins, on the last. However, even though the insole may be accurately located on the last bottom by these pins, there is still the likelihood that without careful arrangement the insole will not remain in position on the last during handling. In addition, the provision of holes pre-formed in the insole requires an additional step in the preparation of the insole and great care is usually necessary to ensure that the holes are correctly positioned for accurate alignment of the insole edge with the featherline of the last.

It is an object of the present invention to dispense with the requirement for an additional step in the preparation of insoles to be temporarily located by means of pins projecting from a last bottom.

It is further an object of the invention to facilitate the formation of apertures in an insole, which apertures are correctly positioned with respect to the peripheral edge of the insole.

The invention provides, in accordance with one of its several features, a last suitable for use in the manufacture of shoes having insoles, said last being provided with at least one pin secured to the last bottom preferably in a forepart region thereof, at least a portion of the pin being capable of passing through an aperture in an insole temporarily to secure the insole to the last bottom, said portion including a cutting edge partially surrounding a recess and capable of penetrating an insole positioned on the last bottom, to form said aperture in the insole, said aperture being in the form of a slot defining a tab or flap in the insole.

The invention further provides, in accordance with another of its several features, a method of temporarily securing an insole to a last bottom including the steps of providing a last with at least one pin secured in the last bottom in a forepart region thereof, said pin being provided with a cutting edge partially surrounding a recess, placing an insole against the last bottom in correct alignment therewith, and applying percussive force to the insole so that it is penetrated by the cutting edge of the last pin to form an aperture in the insole in the form of a slot defining a tab or flap.

Conveniently one or two further pins may be secured in the last bottom to assist in holding the insole in position thereon. If one further pin is used, it may be situated at the heel end portion of the last. Use of two further pins will allow one of these to be situated near the waist portion where an insole may be inclined to "bridge" the last bottom if special care is not taken. These further pins are arranged to penetrate the insole when percussive force is applied thereto, but the apertures so formed need not be in the form of slots as mentioned above but simply formed as a result of a point

or short-line contact with a pin having a pointed or chisel-shaped end. This is because when the last is slipped from the completed shoe, these further pins are required merely to be pulled out of the apertures in the insole in a direction approximately normal to the plane of the heel end portion of the insole. However, the use of such pins in the forepart of the insole would prevent the last from being slipped.

A last according to the present invention is provided with a pin secured in the forepart of the last bottom, which pin has a cutting edge which may be generally C-shaped to cause a tab or flap to be cut in the insole when a percussive force is applied thereto. In a last illustrative of the invention and later to be described in more detail, a pin is secured in the last bottom in a forepart region thereof so that the C-shaped cutting edge thereof is aligned so that the arms of the C are pointing in a generally heelward direction. The pin itself comprises a hollow tubular portion having a substantially circular cross section and, of the 360° of the outer end of the tube, just over 180° is sharpened to a relatively keen edge, the remaining portion being cut away to a level which is at or just above the surface of the last bottom when the pin is secured therein. Percussive force applied to an insole positioned on the last bottom causes a slot to be cut in the insole, this slot defining a C-shaped tab or flap in the insole. The percussive force may be applied by any convenient means but the striking face is best formed of a hard material having some resilience, for instance, polypropylene. When the force is applied to the insole the C-shaped tab or flap is formed and has a tendency to bend out of the plane of the remainder of the forepart of the insole, and to be forced into the recess between the arms of the cutting edge of the pin. This action helps to hold the insole in position on the last bottom. When the time comes to slip the last, the insole will begin to move forward relatively to the last bottom and the tab will slide entirely into the recess folding over as it does so. Continued relative movement between the insole and the last bottom will cause the folded-over tab to be dragged out of the recess and the insole is then free of the pin. The tab or flap will then easily be flattened to restore a smooth surface to the insole by the insertion of a sock, or even the foot of the wearer, into the shoe, the folding-over action of the tab or flap may be facilitated by leaving that portion remaining of the outer end of the tubular portion of the pin that is not sharpened to a relatively keen edge, at a level slightly above the surface of the last bottom and in a blunt state so that it merely causes a slight indentation of the insole to enable the tab to "hinge" along the indentation. Ideally the pin may have a D-shaped cross section where the upright of the D corresponds to the "hinge."

Where there is a possibility that, because of the material of which the insole is made or for some other reason, the tab or flap may tear as it is pulled away from the pin, then the C-shaped slot may be formed with the arms of the "C" pointing in a generally toward direction. The tab or flap will still be pushed slightly into the recess of the pin but not to any great extent, and the depth of the recess need not be great since the tab or flap will not be required to fold over. Indeed, the tab or flap should not be permitted to bend too far out of the plane of the insole or else, during a subsequent toe-lasting operation, the insole may shift heelwardly if the tab or flap accidentally folds. The unbent tab or flap

will press against the inside curve of the C-shaped cutting edge of the pin and is likely to be able to withstand toe-lasting pressures. With this in mind, it will be appreciated that the non-cutting remaining edge of the pin is arranged to be flush with or below the level of the last bottom so as to avoid the formation of a "hinge."

It will also be understood that the tab or flap may be cut to be U-shaped, V-shaped or any suitable shape that will hold it in position when it is forced into the recess.

There will now be described with reference to the accompanying drawings, a method for use in the making of shoes provided by and illustrative of the invention, the illustrative method making use of the illustrative last hereinbefore mentioned. It will be understood that the illustrative method and the illustrative last are described by way of example of the invention only and not by way of limitation thereof.

In the drawings:

FIG. 1 shows a perspective view of the illustrative last;

FIG. 2 is a fragmentary section on line II-II of FIG. 1 on an enlarged scale, showing details of a last pin and an insole temporarily secured to the last bottom;

FIG. 3 shows a perspective view of the last pin of the illustrative last; and

FIG. 4 is a view partly in section of a shoe being slipped from the illustrative last.

In FIG. 1 the illustrative last 2 is shown provided with a metal plate 4 secured to the bottom surface thereof. Embedded in a heel portion of the last bottom are two pins indicated at 6 which project from the metal plate. The main body portion of each pin is provided with circumferential grooves 10 formed therein, and a tip portion of each pin is formed in a chisel-shaped penetrating edge 8. A pin 12 (FIG. 2) is provided in the forepart of the last bottom and comprises a main tubular portion 14 substantially embedded in the last bottom. A C-shaped cutting edge 16 and a part-circular blunt edge 18 of the pin projects from the surface of the last bottom. An external part-circumferential groove 19 is formed in the tubular portion 14 immediately below the cutting edge 16, which edge is formed by machining an inclined surface 30 on the outer end portion of the tubular portion 14. The tubular portion 14 encloses a recess 20. An inner end portion 22 of the tubular portion 14 is in the form of an end wall counter-sunk to receive a screw 24 which secures the pin 12 into the last 2.

In carrying out the illustrative method, an insole 26, preferably pre-moulded to a shape corresponding to (or exaggerated as compared with) that of the bottom of the last 2, is positioned against the last bottom accurately with respect to the featherline of the last 2. Percussive force in the form of a blow from a polypropylene covered hammer head of an impact cylinder, for example from a power nail inserting tool, is applied to the insole in the region of each of the pins 6 and 12 in turn. As each of the last pins 6 penetrate the insole, the material of the insole is deformed around the aperture and tends to be moulded into the grooves 10 to aid in the retention of the insole upon the pin during the lasting operations.

When the cutting edge 16 of the pin 12 cuts through the material of the forepart of the insole a C-shaped slot is formed in the insole and defines a tab 28 which tends, because of the slightly resilient nature of the material of the covering on the hammer head to have been

pushed into the recess 20 by its impact as seen in FIG. 2. The tab is able to hinge out of the plane of the insole because of the indentation made therein by the blunt edge 18, as shown in FIG. 2. Since the diameter of the recess 20 is slightly smaller than the diameter of the circle of which the cutting edge 16 forms an arc, the material of the tab 28 is slightly compressed as it is pushed into the recess thereby affording a grip to aid retention of the insole in place during the lasting operations. This retention is further aided during the toe lasting operation by the insole material being deformed into the groove 19, the heelward pressures of the toe lasting operation serving to press the insole even more firmly into this groove.

When it is required to slip the last from a shoe when completed, the pin 6 will be pulled heightwise of the shoe and be easily removed from the insole. When the last is then moved in a direction substantially heelward of the shoe, the tab 28 hinges about the indentation made by the edge 18 and folds over between the insole itself and the last bottom as shown in FIG. 4, which shows the tab 28 being pulled out of the recess 20 across the inclined surface 30 of the pin 12. When the shoe is freed of the last, insertion of a sock in the shoe ensures that the tab 28 returns to a flat position level with the remainder of the insole.

I claim:

1. A shoe last having at least one embedded member provided with a cutting edge projecting from the last bottom and shaped to cut a tab in an insole forceably applied to the last bottom for holding the insole in registration with the last bottom, said member being recessed to receive said tab.

2. A shoe last according to claim 1 in which said member is a pin having a recess and the cutting edge is formed about a portion of the projecting end to cut a C-shaped tab in the insole.

3. A shoe last according to claim 1 in which said member has a blunt portion projecting from the insole bottom adjacent the cutting edge to form a hinging indentation in the uncut portion of the tab.

4. A shoe last according to claim 1 in which the member is provided with an exterior groove between the cutting edge and the last bottom for receiving a portion of the cut portion of the insole.

5. A shoe last according to claim 1 in which said cutting edge is formed on said member to define spaced legs extending heelwardly of the last bottom.

6. A shoe last according to claim 1 in which said cutting edge is formed on said member to define spaced legs extending toewards of the last bottom.

7. A shoe last according to claim 1 in which said member is received in the forepart portion of the last bottom.

8. A shoe last according to claim 6 in which the heelward portion of the last bottom is provided with at least one sharpened pin on which the heelward end of the insole is impaled.

9. A method of temporarily securing an insole to a last bottom without fasteners driven through the insole into the last including the steps of providing a last with at least one recessed member having a shaped cutting edge projecting from the last bottom, registering an insole with the last bottom, and forcing the insole against the last bottom whereby said cutting edge cuts a tab in the insole which is received in the recess to hold the insole on the last bottom.

10. A method of lasting shoes including the steps of provided a last with at least one recessed member having a shaped cutting edge projecting from the forepart of the last bottom, registering an insole with the last bottom, forcing the insole against the last bottom whereby said cutting edge cuts a tab in the insole which

is received in the recess to hold the insole on the last bottom, lasting a shoe upper on the last and insole, and removing the last from the lasted shoe so the tab is slipped from the recess.
